[57] CLAIM

The ornamental design for a low profile passive infrared sensor, as shown and described.

DESCRIPTION

FIG. 1 is a front perspective view of the low profile passive infrared sensor of the present invention.

FIG. 2 is a right side elevational view of the low profile passive infrared sensor, with a left side elevational view being symmetrically identical therewith.

FIG. 3 is a top plan view of the low profile passive infrared sensor; and,

FIG. 4 is a bottom plan view of the low profile passive sensor.
